UNITED STATES PATENT OFFICE.

HERMANN C. LUTZ, OF NEW YORK, N. Y.

PIANO-FORTE ACTION.

SPECIFICATION forming part of Letters Patent No. 366,781, dated July 19, 1887.

Application filed March 28, 1887. Serial No. 232,648. (No model.)

To all whom it may concern:

Be it known that I, HERMANN C. LUTZ, of the city and county of New York, in the State of New York, have invented a new and useful 5 Improvement in Piano-Forte Actions, of which the following is a specification.

My invention relates to those actions, whether for grand or upright pianos, in which the levers or members on which the keys act are supported by a bar or rail which is movable transversely to its length by the action of the soft-pedal; and the object of my invention is to maintain such levers or members in their proper relation to the surfaces of the keys which 15 act upon them, notwithstanding that the forward movement of the bar or rail acts to lift said levers or members, as well as to move them forward.

The invention consists in the combination, in 20 a piano-forte action, with the keys and levers or members through which they operate the hammers, and which are provided with contact-screws on which the keys act, the keys having upon their upper surfaces rearwardly-extending 25 inclines on which said contact-screws bear, of a bar or rail supporting said levers or members, and which is movable transversely to its length, and connections through which said bar or rail, with the levers or members which 30 it supports, may be moved forward by the soft-pedal of the instrument.

In the accompanying drawings, Figure 1 represents a grand action embodying my invention with the soft-pedal off. Fig. 2 is a 35 corresponding view representing the parts as operated by the soft-pedal or with the soft-pedal on; and Fig. 3 represents an upright action also embodying my invention, the parts being shown as with the soft-pedal off.

Similar letters of reference designate corresponding parts in the several figures.

The line A represents the position of the strings. B designates the hammer, secured by its flange b to the usual hammer-rail, B'. 45 C designates the hammer-rest rail or rest, and D designates the lever or member, which is provided with a contact-screw, d, and through which the key E, fulcrumed at e, acts upon the hammers.

50 Referring, now, to Figs. 1 and 2, F designates a bar or rail, which has secured to it the flanges

d' of the levers or members D, and which is so supported that it may be moved transversely to its length forward and backward. Provision for such movement is here afforded by hinging the bar or rail F at f to the rail G, and suitable connections are employed through which the movement of the soft-pedal will throw forward the bar or rail F and the members or levers D carried by it. I have here 55 represented a bell-crank, H, which is fulcrumed at h, and one arm of which is connected by a rod, h', with the bar or rail F, while its other arm is connected by a rod, h'', with the soft-pedal. (Not here shown.) By 60 this or other suitable connections the movement of the soft-pedal will throw forward the rail or bar F and the levers or members D, carried by it, into the position shown in Fig. 2, and will thereby lift and hold the hammers B 70 up nearly to the strings A. By the forward movement of the rail or bar F and the levers or members D the contact screws or points d will be naturally carried upward slightly away from the keys E, and such upward movement 75 would, if no provision for preventing it were provided, necessitate a longer movement of the key before it comes into action upon the screw d, and would render the touch of the keys variable or different when the soft-pedal is applied from what it would be if the soft-pedal were out of action. To avoid such variable touch, I form upon the tops of the keys or key-levers rearwardly-extending inclines e', upon 80 which the contact-screws d bear. When the 85 bar or rail F is swung forward by the application of the soft-pedal, the contact-screws d are moved forward over a portion of the inclines e', which have greater projection above the keys or key-levers E, and therefore any 90 material lost motion between the keys and the screws d is avoided.

In the example of my invention shown in Fig. 3 the levers or members D, carrying the screws d, on which the key-levers or keys E 95 act, are hung by flanges d' to a rail or bar, F, as before described, and this rail or bar has upwardly-extending arms f', which are pivoted at f to the sides of the case or to the end portions or uprights of the action. Connections for moving the bar or rail F transversely 100 to its length, and which are similar to those

before described, are here shown. A bell-crank lever, H, fulcrumed at h, has its arms respectively connected by rods h' h'' with the bar or rail F and the soft-pedal. By a link-and-lever connection, i I, the bar or rail F is connected with the hammer-rest rail C. When through the connections here shown the bar or rail F is moved or swung forward by the soft-pedal, the contact-screws d are brought into contact with the portion of the inclines e' having greater projection above the keys E, and by the rods j, through which the levers or members D act upon the other portions of the action, the hammers are brought forward nearer to the strings A, and at the same time, through the link i and the lever I, the hammer-rest rail C is swung rearward to support the hammers. The action of the inclines e' in maintaining the uniform touch of the keys is the same as before described with reference to Figs. 1 and 2.

What I claim as my invention, and desire to secure by Letters Patent, is—

In a piano-forte action, the combination, with the keys and the levers or members through which they operate the hammers, and which are provided with contact-screws d, on which the keys act, the keys having upon their upper surfaces rearwardly-extending inclines, on which said contact-screws bear, of a bar or rail supporting said levers or members, and which is movable transversely to its length, and connections through which said bar or rail, with the levers or members which it supports, may be moved forward by the soft-pedal of the instrument, substantially as herein described.

H. C. LUTZ.
